CAMMED HINGE

Herbert Krause, Chicago, Ill., assignor to Chicago Forging and Manufacturing Company, Chicago, Ill., a corporation of Delaware

Filed Dec. 2, 1960, Ser. No. 73,300
10 Claims. (Cl. 16—128.1)

This invention relates to hinge mechanisms and particularly to those employed in support of automobile hoods and the like.

One purpose of the invention is to provide an articulated hinge having a plurality of movable members and effective to cause simultaneous forward and upward movement of one of the hinged members.

Another purpose is to provide an articulated hinge having a yielding means, there being elements of the hinge effective to maintain said yielding means under substantially constant tension throughout the entire excursion of the hinge between closed and open position.

Another purpose is to provide an articulated hinge mechanism having a yielding means maintained at substantially continuous tension at all positions of said hinge, the means employed for maintenance of said continuous tension being effective also to urge the hinge into each of its terminal positions.

Another purpose is to provide an articulated hinge mechanism having a yielding means secured thereto and having associated therewith a pivoted element effective to control said yielding means throughout the excursion of said hinge mechanism.

Another purpose is to provide an articulated hinge mechanism including a pivoted element serving to control the tension of the yielding means associated with said mechanism and additionally to function as a cammed abutment for said hinge.

Other purposes will appear from time to time during the course of the specification and claims.

I illustrate my invention more or less diagrammatically in the accompanying drawings wherein:

FIGURE 1 is a side elevation illustrating the hinge of the invention in closed position;

FIGURE 2 is a top plan view in partial cross section and with parts broken away; and

FIGURE 3 is a view similar to that of FIGURE 1 with the hinge of the invention shown in open position.

Like parts are indicated by like numerals throughout the specification and claims.

Referring now to the drawings, and particularly to FIGURE 1 thereof, the numeral 1 illustrates generally a mounting plate. The plate 1 may be of substantially continuous planar extension on both sides and may be of relatively thin plate stock. Attaching apertures 2 may be formed in the plate 1 for attachment of the plate to the body or one of the members to be hinged. For example, the plate 1 may be attached to an automobile body, it being understood that a pair of the mechanisms illustrated in FIGURE 1 might be suitably employed in connection therewith.

Pivotedly mounted, as at 4, on one side of plate 1 is an arm or hinge lever 5, the pivotal mounting of the arm 5 being positioned adjacent one end of the arm 5. The opposite end of arm 5 is pivotally secured as at 6 to a rear end portion of a mounting bracket 7, it being understood that the bracket 7 would, in the use of the hinge, be secured to the other member to be hinged, e.g. the hood cover for the hood body to which the plate 1 is secured.

The bracket 7 has a forward portion pivotally secured, as at 8, to an end portion of a link arm 9. The opposite end portion of link arm 9 is pivotally secured as at 10, as may be best seen in FIGURE 3, to an end portion

2

of a second hinge arm or lever 11. The opposite end of lever 11 is pivotally secured as at 12 to the plate 1 on the opposite side thereof from the side to which hinge arm 5 is pivotally secured. It will be further noted that the pivot points 4 of lever 5 and 12 of lever 11 are spaced on plate 1 and that the arms or levers 5 and 11 extend in substantially opposite paths when the hinge is in closed position and in intersecting paths when the hinge is in open position.

10 An opening, which may take the form of an arcuate slot and which is indicated at 15, is formed in the plate 1 between the pivoted points 4 and 12. The lever 5 has a laterally offset segment 16 overlying and traveling above the opening 15 in the excursion of the hinge from closed to open position. A pin 17 is secured to the lever portion 16 and extends through the opening or slot 15. A hinge link 18 is pivotally secured to the pin 17 on the opposite side of plate 1 from lever 5, the pin 17 being pivotally secured to the link 18 at one end of the link 18. 15 The link 18 is pivotally secured adjacent its opposite end, as at 19, to the lever 11 at a point intermediate the ends thereof. As may be best seen in FIGURE 2, the lever 11 has its intermediate major segment offset to provide a space between the lever 11 and the plate 1 when the lever 11 is in closed position and to accommodate reception of the link 18, the latter having offset end portions to provide for sliding contact of the link portion secured to the pin 17 with the plate 1 along and about the opening 15 during the excursion of the hinge between closed and open positions.

The hinge lever 5 has an angularly disposed end edge portion 20 and elongated flange 21 extends laterally from the edge 20 of lever 5 to provide an elongated, flat abutment segment.

20 35 Pivotedly mounted, as at 30, to the plate 1 and at a point beyond the pivot point 4 from the pivot point 12 is a control or cam member 31. It will be observed that the member 31 is pivoted to the plate 1 adjacent one of the ends of member 31. The opposite end of cam member 31 has formed therein an aperture 32 adapted to engage with one end of a yielding means, such as the spring 33, the opposite end of which is secured to an ear 34 extending laterally from lever 5 at a point adjacent the pivot 6. The control cam member 31 has an edge disposed angularly with respect to a line drawn between the pivot point 30 and the aperture 32, the said edge being indicated by the numeral 35 and lying substantially parallel with the edge 20 of lever 5 when the hinge is in closed position as illustrated in FIGURE 1. 40 45 50 An elongated flange 36 extends laterally from and along the edge 35 for abutment with the abutment flange 21 on lever 5.

The use and operation of my invention are as follows:

It will be understood that bracket member 7 is secured, 55 by any suitable means, to the underside of an end portion of the member to be lifted, for example the hood cover of an automobile. Portions of attaching apertures for bracket 7 are illustrated, for example in FIGURE 2, as indicated by the numerals 37. The bracket member 7 is of L-shape in cross section, comprising a hood cover-receiving surface 7a and a hinge-connecting segment 7b. It will be further understood that the opposite end portion of the member to be raised, for example the hood cover of an automobile, would be positioned to the right 60 of the figures as they appear in the drawings herein. As the hood cover is raised the rear portion thereof, through the mediacy of the bracket 7 and the present hinge mechanism, is caused to move in an upward arc moving to the right, as the figures are shown in the drawings, a slight distance as initial upward movement of the hood cover takes place. As the cover is raised further the hinge moves through its excursion from the closed posi-

tion illustrated in FIGURE 1 to the fully open position illustrated in FIGURE 3.

A close examination of the drawings will illustrate the fact that, as the hinge moves from closed to open position the abutment surface 21, with its rounded end portion 21a, rides along the abutment surface 36 of the cam 31 to rotate the same in a clockwise direction, as the parts are shown in the drawings, the initial contact of rounded abutment surface 21a with elongated surface 36 occurring at a point adjacent the aperture 32 and substantially remote from the pivot point 30 of cam 31.

Similarly, as the hinge moves from fully open to closed position the action of spring 33 is effective to rotate the cam 31 in a counterclockwise direction as the parts are shown in the drawings, to retain the same in contact with member 5.

Thus the spring 33 is maintained under substantially continuous tension throughout the excursion of the hinge and at all positions of the hinge. As the drawings are intended to illustrate, a spring 33 is caused to have substantially the same extension at all positions of the hinge. The arrangement of the parts, and the provision of cam member 31, is effective, however, to accomplish all of the functions previously required of yielding means employed in hinge structures of the prior art while avoiding the excessive stretching of springs previously employed as the hinge moved through its excursion from closed to open position and return.

The spring 33 acting through lever 5 and cam 31 causes contact of the abutment surface 36 with the abutment surface 21 to urge the hinge toward closed position when the hinge is in such position as illustrated in FIGURE 1. Similarly the parts are dimensioned to cause the rounded abutment segment 21a of surface 21 to move beyond the lower curved segment 36a of cam 31 when the hinge is in fully open position as illustrated at 33 in FIGURE 3. In this position the spring 33 acting through cam 31 and abutment segments 36a, 21a is effective to urge the hinge toward open position. The overlap 38 is of sufficient area to provide for such retention of the hinge in open position while at the same time is of such minimum area that, combined with the rounded confirmation of the abutment surfaces, the resistance of the hinge toward movement in the direction of return to closed position may be overcome with slight manual pressure on the hood cover to which the bracket 7 is attached. Since the cam is pivoted at 30, it returns to the position illustrated in FIGURE 1 as the hinge moves toward closed position, thus maintaining a substantially continuous and identical distance between the aperture 32 and the ear 34 to which the opposite ends of the spring 33 are attached and the spring is therefore not subjected to any major stretch or tensioning as the hinge moves through its excursion.

Whereas I have described and claimed an operative device, I wish it to be understood that this showing is to be taken in an illustrative or diagrammatic sense. There are many modifications of the invention that will fall within the scope of the invention that will be apparent to those skilled in the art. For example, while the spring 33 is described as being maintained at substantially a continuous tension throughout the excursion of the hinge, minute variances in tension, such as those caused by variance in manufacturing tolerances, for example, may be permitted as the hinge moves through its excursion without departing from the nature and scope of my invention, it being understood that such slight variances are so far removed from the wide ranges of tension to which springs employed in hinges of the prior art have been subjected as to be relatively inconsequential. Similarly, it will be noted that flange segments are illustrated as formed along a major portion of most of the edges of lever 5 and cam 31, the same being employed for manufacturing or strength purposes, the abutment flange surfaces 21, 36 and 21a, 36a being employed as the active elements in the cooperation of the cam 31 and lever 5.

The scope of the invention, therefore, should be limited only by the scope of the hereinafter appended claims.

I claim:

1. An articulated hinge mechanism comprising a mounting plate, a first hinge lever pivotally mounted adjacent one of its ends on said plate, a second hinge lever pivotally mounted adjacent one of its ends on said plate at a point spaced from the pivot point of said first hinge lever, a link arm pivotally mounted adjacent one of its ends to the opposite end of said second hinge lever, a bracket pivotally mounted adjacent one of its ends to the opposite end of said first hinge lever, the opposite end of said bracket being pivotally connected to the opposite end of said link arm, a cam member pivotally mounted directly on said plate at a point spaced from the pivot points of said first and second hinge levers, a yielding means extending between and secured to said cam member and said first hinge lever, abutment surfaces on said first hinge lever and said cam member, said abutment surfaces being positioned for sliding contact throughout the excursion of said articulated hinge mechanism from fully closed to fully open position.

2. An articulated hinge comprising a mounting plate, a plurality of hinge levers pivotally mounted on said plate, a mounting bracket, said hinge levers being pivotally mounted to said bracket, a separate cam member pivotally mounted directly on said plate, an abutment surface on said cam member, an abutment surface on one of said hinge levers, said abutment surfaces being positioned for sliding contact with each other throughout the excursion of said hinge from fully closed to fully open position and yielding means connected to said cam and said last named hinge lever.

3. In an articulated hinge, a mounting plate, a plurality of hinge levers pivotally mounted on said mounting plate, a bracket, said hinge levers being pivotally mounted on said bracket, one of said hinge lever being mounted for rotation in one direction as said hinge moves from open to closed position, a cam member pivotally mounted directly on said plate, said cam member having an abutment surface positioned for continuous contact with said last-named hinge lever throughout the excursion of said hinge between closed and open position, yielding means extending between and secured to said cam member and said last-named hinge lever, said cam being positioned for movement in said one direction as said hinge moves from closed to open position, said last-named hinge lever and said cam being mounted for movement in the opposite direction as said hinge moves from open to closed position, whereby said yielding means is maintained at substantially continuous tension throughout the excursion of said hinge between closed and open position.

4. In an articulated hinge, a mounting plate, a plurality of hinge members pivotally mounted on said plate, a bracket, said hinge members being pivotally mounted on said bracket, one of said hinge members having an abutment surface, a separate cam member pivotally mounted on said plate and having an abutment surface positioned for contact with said last-named hinge member abutment surface throughout the excursion of said hinge between closed and open position, a spring having one of its ends secured to said cam member and having its opposite end secured to said last-named hinge member, said cam member and said last-named hinge member being mounted for rotation in the same direction as said hinge moves toward open position and in the same opposite direction as said hinge moves toward closed position whereby the distance between the points at which said spring is connected to said cam and to said last-named hinge member is maintained substantially unchanged throughout the excursion of said hinge between closed and open position.

5. The structure of claim 4 characterized by and including rounded end segments on said abutment surfaces positioned for overlapping contact when said hinge is in fully open position.

6. The structure of claim 4 wherein said abutment surfaces are positioned in relation to the pivot points of said cam and said last-named member to cause said cam, under the influence of said spring, to urge said member toward hinge-closed position when the hinge is in closed position.

7. In an articulated hinge a mounting plate, a plurality of hinge levers pivotally mounted on said plate, a bracket, a cam pivotally mounted directly on said plate at a point spaced from the pivotal mounting of one of said hinge levers, said cam having an abutment surface positioned between its pivot point and the pivot point of said last-named hinge lever, said last-named hinge lever having a cooperating abutment surface positioned for continuous contact with said cam abutment surface and positioned between the pivot point of said hinge lever and the pivot point of said cam, a spring having one of its ends secured to said cam at a point between said cam abutment surface and said cam pivot point, said spring having its opposite end secured to said last-named hinge lever at a point beyond said hinge lever pivot point from said hinge lever abutment surface, said cam and said last-named hinge lever being mounted for rotation in the same direction as said hinge moves between its closed and open positions.

8. The structure of claim 7 characterized by and including a rounded abutment segment on one of said cam surfaces whereby said abutment surfaces are moved into a minimum over-center position when said hinge is in its fully open position.

9. An articulated hinge comprising a mounting plate, a plurality of hinge levers pivotally mounted on said plate, a bracket, said hinge levers being pivotally mounted on said bracket, one of said hinge levers having an elongated

abutment surface, said abutment surface having a curved segment at one of its ends, a cam pivotally mounted directly on said plate and having an elongated abutment surface positioned for continuous sliding contact with said hinge lever abutment surface, said cam surface having a rounded segment at its end opposite that opposed to the rounded segment of said hinge lever abutment surface, said rounded abutment segments being positioned for overlapping contact when said hinge is in fully open position.

10. An articulated hinge comprising a mounting plate, a plurality of hinge levers pivotally mounted on said plate, a bracket, said hinge levers being pivotally mounted on said bracket, a cam pivotally mounted on said plate, said cam having an abutment surface positioned for continuous contact with one of said hinge levers as said hinge is moved between its closed and open positions, and yielding means connected to said cam and said last-named hinge lever and positioned to urge said cam abutment surface into continuous contact with said last-named hinge lever.
